[57] CLAIM

The ornamental design for a light diffuser or the like, as shown and described.

DESCRIPTION

FIG. 1 is a perspective view of a light diffuser or the like showing my new design; and

FIG. 2 is a top plan view thereof, the bottom view being a mirror image; and

FIG. 3 is a front elevational view thereof; and

FIG. 4 is a side elevational view thereof as seen from the left of FIG. 2, the side seen from the right of FIG. 2 being a mirror image.

FIG-1

FIG-2

FIG-3

FIG-4
